Inventor
CHARLES P. EISENHAUER,

By *Paulmin Paulmin*,
Attorney

UNITED STATES PATENT OFFICE.

CHARLES P. EISENHAUER, OF DAYTON, OHIO, ASSIGNOR TO THE DURO COMPANY, OF DAYTON, OHIO, A CORPORATION OF OHIO.

VALVE.

Application filed December 2, 1925. Serial No. 72,702.

My invention relates to valves.

It is the object of my invention to provide a quick-acting, snap-action valve which will convert the direction of the passage of fluid from one direction to the other and provide for the exhausting of the fluid from hydrostatic valves which are controlled by the master needle valve which is the subject matter of this application.

10 It is my object to provide a valve which will move positively and quickly from one position to the other.

Referring to the drawings:—

15 Figure 1 is a section through this valve; Figure 2 is a section through a portion of the needle valve showing the parts in exhausting position.

Referring to the drawings in detail, 1 is a bracket supporting a tubular housing 2, the lower end of which is threaded to a casing 3. This casing supports a pair of spaced arms 4 on which are pivoted at 5 the links 6 having shoulders 7. The upper free ends of these links are connected together by a helical spring 8 which tends to draw them together. The shoulders on these links engage with the shoulders 9 on the valve stem 10. The upper end of this valve stem is provided with a cross pin 11 which engages with a helical spring 13 contained within a supporting casing 14, one end of which is slidably mounted on the valve stem 10 and the other end of which is connected to an actuating lever 15. The action of this lever is resisted by the helical spring 16 which is connected to the housing 14 at one end and to a suitable support at the other.

20 The lower end of this valve stem is connected to a collar 17, the bottom of which engages a helical spring 18 which is supported on the casing 3. Within the bottom of this casing 3 is a fifth helical spring designated 19. The spring presses a packing 20 and washer 21 around the valve stem 22 within the casing 23 which is threaded within the casing 3. This casing 23 is provided with a chamber 24 having an exhaust port 25 and an inlet port 26. This inlet port communicates with a chamber 27 within a casing 28 threaded on the casing 23 at its lower end. This chamber 27 is provided

with an inlet port 29 for the incoming water which is distributed through the distribution ports 30 and 31 or through the exhaust port 26.

Method of operation.

55

Assuming the parts are in the relation shown in Figure 1 and pressure is applied to the casing 14 through the lever 15, the following operations and effects are produced: The pressure on the lever 15 tends to lower the casing 14 and compress the spring 13, which bears against the valve stem 10. As the casing 14 is lowered the upper inner faces of the links 6 are engaged by the inclined surfaces 32 on the lower part of the casing 14 to the end that the links 6 are forced apart. As the links 6 move away from each other, due to the action of the casing 14, the shoulders 7 are 65 brought out of engagement with the shoulders 9, and as soon as these shoulders are released from engagement with each other, the valve stem 10, having no support, yields to the action of the spring 13 and the pressure on the lever 15 to open the port 26, due to the immediate lowering of the valve 70 34. This opening of the port 26 is instantaneous because before the shoulders 9 are released from the shoulders 7 sufficient pressure has been accumulated in spring 13 so that as soon as the shoulders are released from each other the valve stem immediately drops 75 and opens the port 26.

It is understood that the pressure on 15 80 works against spring 16 and spring 18 at all times tends to close the port 26 by means of the valve 34.

Assuming that the valve stem and associated mechanism are in their lowered position and the pressure is removed from the lever 15. When this takes place the spring 16, which has been expanded due to the downward pressure on the lever 15, and the spring 18, which has been compressed, immediately snap the valve member 34 to a position to close the port 26. Immediately after the pressure is removed from the lever 15 the cam surface 32 on the casing 14 begins to release the upper inner surfaces of 95 the links 6, thereby permitting these links to gradually come together, but while this

action is taking place the whole valve stem is also moving upwardly so that by the time that the cam 32 is removed from the upper part of the link 6 the shoulders 9 are even 5 with or about past the shoulders 7. In this condition the links 6 are brought together by means of the spring attached to the upper ends thereof so that the valve stem is again locked in its upper position, as indicated in 10 Figure 1.

It is of course understood that I desire to comprehend within my invention such modifications as may be necessary to adapt it to varying conditions and uses.

15 Having thus fully described my invention, what I claim as new and desire to secure by Letters Patent, is:

20 1. In combination, a needle valve, an inlet port and an exit port controlled thereby, means to actuate said valve and means to forcibly move said valve and hold it to and in its final position, said last mentioned means consisting of separately acting 25 springs acting in opposite directions.

25 2. The combination in a needle valve, of a valve stem, a valve member adapted to close entrance and exit ports in a chamber having distribution ports, a distribution chamber, an exhaust chamber, and spaced 30 separately and oppositely acting means to forcibly hold and assist in the closing or opening of said valve so that the valve will be snapped into open or closed position.

35 3. In a needle valve, a distribution chamber having distribution ports, an inlet port and an exhaust port, an exhaust chamber, means for forcing the valve open, means for yieldingly closing said exhaust chamber, link means and link released means to 40 abruptly snap the valve closed or open and hold it in such open or closed position.

45 4. In a needle valve, a distribution chamber having distribution ports, an inlet port and an exhaust port, an exhaust chamber, means for forcing the valve open, means for yieldingly closing said exhaust chamber, means to abruptly snap the valve closed or open and hold it in such open or closed position, said means consisting of shoulders 50 on the needle valve stem and shouldered links yieldingly held against said first-mentioned shoulders at one end and pivoted on a support at the other, and a support for guiding said valve stem.

55 5. In combination, a valve chamber having ports, a valve member, a valve stem, means to yieldingly resist the movement of said stem and member, means to actuate said resisting means, a second yielding means engaged by the actuating means and the valve stem adapted to actuate the valve stem when a predetermined compression is

reached overcoming the resistance of the resisting means suddenly.

65 6. In a valve mechanism, a housing, a valve operating means mounted within said housing, said valve operating means including a valve stem, a casing slidably fitting over one end of said valve stem, a spring in said casing engaging the valve stem to hold the casing and the stem in expanded relation to each other, means in the housing to engage the stem to hold the valve closed, means on the casing to engage and release the last-named means when the casing is moved on 70 the stem, and means for applying pressure to the casing whereby the spring is compressed, the stem-holding means is released and the valve is instantaneously opened.

75 7. In a valve mechanism, a housing, a valve operating means mounted in said housing and consisting of a valve stem, a casing slidably fitting over the end of the valve stem, a spring in said casing engaging the valve stem to hold the casing and the stem 80 in extended relation to each other, spring operated means in the housing to engage the stem to hold the valve closed, means associated with the casing and adapted to engage and release the last-named means when 85 the casing is moved against the action of the spring, and means for applying pressure to the casing whereby the spring pressed stem-holding means is released and the valve is instantaneously opened.

90 8. In combination, a valve and valve stem, an inlet part and an outlet part controlled thereby, links to engage the stem to lock said valve in one position, and a casing inclosing the end of said valve stem and 95 adapted on being pressed onto said stem to engage said links to release the valve stem whereby the valve will shift to another position.

100 9. In combination, a valve and a valve stem, an inlet part and an outlet part controlled thereby, links to engage the stem to lock said valve in one position, a casing inclosing the end of said valve stem, and a spring between said casing and said stem, 105 said casing adapted on being pressed against said spring to engage said links to release the stem whereby the valve will snap to another position due to the action of the 110 spring in said casing.

115 10. In combination, a valve and a valve stem, an inlet part and an outlet part controlled thereby, holding means engaging said stem to hold said valve in one position, and means movable longitudinally of said stem to first release said holding means and then to shift said valve to another position.

In testimony whereof, I affix my signature.
CHARLES P. EISENHAUER.
